ATTORNEY.

UNITED STATES PATENT OFFICE.

ELLEN V. CHEESEMAN, OF PASADENA, CALIFORNIA.

INCENSE BURNER.

Application filed January 31, 1927. Serial No. 164,754.

The present invention relates to novelty incense burners and pertains more particularly to a combination doll or ornament and an incense burner to provide both ornamentation and utility.

The invention has for its principal object the provision of a novel though useful and efficient incense burner.

Another object of the invention is to provide an incense burner which is readily filled or replenished and in which the heat and ash are at all times safely out of contact with other objects or surfaces which might otherwise become damaged thereby.

Another object of the invention is to provide a novelty doll suitable for gifts, favours and the like, or suitable for prizes at amusement concessions and like places.

The usual incense burner has among other objections a tendency to become quite hot and to scorch surfaces with which it comes in contact. It is therefore another object of the invention to provide an incense burner in which the burning medium and the surrounding heated products of combustion are well insulated from all other objects as well as from the major portion of the burner itself, whereby the incense burner may be handled at will or placed any place without harmful results.

Another object of the invention is to provide an incense burner which is sanitary and cleanly by reason of being readily cleaned internally.

It is common to construct incense burners to resemble various ornamental objects, and it is common to burn incense in ornamental receptacles which are either partially suited to such use or which are expressly designed for such use. The materials of which such devices can be made is limited to suitable refractory materials, and any exterior decoration or finish is quickly damaged by the heat generated internally. It is therefore still another object of my invention to provide an ornamental or novelty incense burner, which may be supplied with delicate or ornate exterior decorations, without normal possibility of such decorations being effected by the internally generated heat.

The correct burning of incense is a scienc-

tific matter, or at least should be, inasmuch as for best results the amount of air reaching the burning product should be limited and controlled. It is therefore another object to provide an incense burner in which the combustion is controlled and efficient.

The efficient burning of incense involves proper dissemination of the resultant fumes throughout the air external to the burner, and it is therefore another object of the invention to promote positive and sustained ejection of the fumes from the burner, and to maintain such escaping fumes at a suitable temperature so that they are sufficiently mobile when liberated to a colder atmosphere.

My invention contemplates the provision of novelty by causing the fumes to emanate in a novel and interesting manner, and it is another object of the invention to produce a simple device which will produce the required novel effect.

Other objects and advantages of my invention will appear hereinafter.

I have illustrated my invention by the accompanying drawings, in which:

Figure 1 is a perspective view of one practical embodiment of my invention.

Figure 2 is a vertical sectional view thereof.

Figure 3 is a view on cross section on a line 3-3 of Figure 2.

Figure 4 is a section on line 4-4 of Fig. 3.

In carrying out my invention I provide a doll or other suitable figure or replica, which assumes an interesting or realistic appearance by the issuance of smoke therefrom. The doll may be a figure of a person smoking a cigarette, for example, or any other suitable object may be represented, which object is rendered more realistic by issuance of smoke therefrom.

In the present embodiment the doll 1, of which the head and bust, only, is shown, is representative of a woman smoking a cigarette. The doll is accordingly constructed with a cigarette 5 protruding from between the slightly parted lips 6 thereof. The head 7 of the doll is hollow to enclose the air space 8.

In order to carry out my desire to produce a truly ornamental or novel incense burner,

I provide the doll with any suitable exterior decorations, which may be actual rater than delineated. In other words, real or imitation hair ^{7a} may be applied to the head, and the clothing may be actually composed of high grade fabric. External or surface decoration, such as coloring of the face, eyes, etc., may be resorted to without fear of such decoration being changed by heat.

10 The doll is provided with the body 9, which need not be hollow, and may represent the complete human figure, or it may be a bust, or the body may be a pedestal, only. In fact, any usual construction may be employed as is common to articles of the same outward appearance.

15 From the body there rises a suitable refractory cylindrical member or plug 10, which may be removably fitted or screw threaded into a socket 11, provided in such body. The upper surface of the member 10 is cupped, as at 12, to hold an incense cone 13 and to retain the ashes thereof. The member 10 rises above the base and serves for holding the head firmly in place. The neck 14, integral with the head, is tubular and fits snugly over the member 10, coming to rest on the shoulder 15. A neck ornament delineated on the figure in relief, such as at 16, serves to obscure the joint between the neck and body.

20 Directly within the neck, and forming a suitable refractory lining therefor, I provide a refractory sleeve 17. The sleeve proper forms the snug fit with the member 10, so that an air space ^{17a} surrounds the member 10 to prevent heat from passing rapidly to the neck of the doll.

25 The sleeve continues in an integral hollow horn 19, which curves upwardly and forwardly toward the parted lips of the figure. This horn is of substantially the same cross sectional area until it turns toward the lips, and up to the turn it is substantially round in cross section. The forwardly directed portion of the horn is changed gradually in cross section to form a slit-like channel 20, leading to an open end 21 thereof. This open end terminates between the parted lips and the horn at this point is preferably joined to the lips.

30 The entire space formed by the sleeve and horn is isolated from the atmosphere except where its open end communicates therewith. The cigarette is in the form of a tube having a perforated outer end 22; the bore of the tube extending into the horn, so that some of the smoke or fumes may escape through the perforated outer end of the cigarette.

35 To place the device in operation, the head is removed from the member 10, and a lighted incense cone is placed in the cupped portion of the member 10, and the head is replaced. The air in the horn supplies

oxygen for first combustion, and owing to the limited amount of air in the horn, the air contents of the horn becomes quickly heated. The resultant products of combustion, by reason of the retained heat, rapidly expand and escape through the cigarette to represent smoking thereof.

40 Since the member 10 is surrounded by air, and since it has an air pocket below it, it does not readily transmit its heat to the body or head of the doll, and thus the heat is retained, while the body, head and neck are protected. The same is true of the horn and head, the head holding dead air around the horn to insulate same. Since the heat is conserved, the products of combustion are kept at such temperature as to cause them to issue in a well defined stream through the parted lips. After passing the parted lips, the temperature of the products of combustion is still sufficient to cause them to rise in a fairly defined column through the surrounding atmosphere. Obviously, the products of combustion issuing in a somewhat defined stream, adds to the efficiency of the incense burner and particularly to its novel appearance. The doll appears to be actually exhaling a thin column of smoke, while the cigarette is seen to smolder quite realistically.

45 New atmospheric air in limited quantities, just sufficient to keep up combustion without diluting the products too greatly, may find its way into the horn through the parted lips periodically. If the combustion begins to wane, the temperature of the small volume of air in the horn would be lowered, creating a pressure reduction and induction of new air.

I claim:—

1. In a novelty incense burner, the combination of a body, an incense burner rising from said body, a hollow member representative of a head and neck and provided with an outwardly opening aperture representative of the mouth of said head, a hollow horn fitted within said neck in spaced coaxial relation to provide an air chamber between such horn and neck; said horn extending to such mouth aperture and being appreciably smaller than the interior of the head whereby the hollow head forms an air space around said horn; the interior of said horn being isolated from communication with the interior of said head, and said head being removably held to said body by reason of that portion of the horn within the neck being a close fit around said incense holder.

2. In a device of the class described, a hollow member representative of a human head provided with a facial aperture, an incense holder within said hollow member, and a horn providing direct communication between said aperture and said incense burner;

said horn being of relatively small volume as compared with the volume of said hollow member and completely isolating contained air from other parts of the interior of said hollow member.

3. In a device of the class described, a hollow member representing a human head and

provided with a mouth aperture, an incense holder within said hollow member, and a hollow horn leading from said incense holder to said mouth aperture; said horn having communication with the external atmosphere only through such facial aperture.

ELLEN V. CHEESEMAN.
